F. A. HEALY

HEATED WINDSHIELD

Filed April 1, 1924

INVENTOR.
Flora A. Healy

BY *H. G. Manning*

ATTORNEY.

UNITED STATES PATENT OFFICE.

FLORA A. HEALY, OF WALLINGFORD, CONNECTICUT.

HEATED WINDSHIELD.

Application filed April 1, 1924. Serial No. 703,508.

To all whom it may concern:

Be it known that I, FLORA A. HEALY, a citizen of the United States, and a resident of Wallingford, county of New Haven, and

- 5 State of Connecticut, have invented certain new and useful Improvements in Heated Windshields, of which the following is a specification.

This invention relates to glass windshields 10 for automobiles, trolley cars, locomotives, and the like, and more particularly to a heated windshield for preventing the accumulation of moisture in the form of mist, frost, etc., which might interfere with the 15 clear vision of the driver.

One object of this invention is to provide a heated windshield of the above nature comprising a double-walled glass compartment provided with interior heating means 20 to maintain the glass panes of the windshield at a relatively high temperature.

A further object is to provide a device of the above nature having means to prevent the heat of the heating element from directly 25 radiating upon the glass surfaces, in order to prevent the possibility of cracking due to overheating.

A further object is to provide a heated windshield which will be simple, inexpensive 30 to manufacture, easy to install, and very efficient and durable in use.

With these and other objects in view, there has been illustrated on the accompanying drawing, the preferred form in which 35 the invention may be conveniently embodied in practice.

Fig. 1 represents a front view of an electrically heated windshield, with certain parts broken away for clearness.

40 Fig. 2 is a fragmentary perspective view of one side of said windshield showing the manner in which the electric heating element is mounted and shielded from the glass panes.

45 Fig. 3 is a sectional view taken along the line 3—3 of Fig. 1, looking in the direction of the arrows.

Fig. 4 is a fragmentary perspective view 50 of an ice scraping device for assisting the operation of said heated windshield.

Referring now to the drawings in which like reference numerals denote corresponding parts throughout the several views, the numerals 10 and 11 indicate respectively the 55 front and rear glass panes of the windshield. The glass panes 10 and 11 are supported by

a frame comprising a top member 12, side members 13 and 14, and a bottom member 15, said members being preferably of wood and T-shaped in cross-section, as more clearly shown in Figs. 2 and 3 of the drawing.

60 A pair of rectangular frames 16 and 17 of thin metal are attached to the front and rear of the wooden frames, just described, in any suitable manner, as by screws 18. A series of four cylindrical porcelain tubes 19, 20, 21 and 22, serve to support within the frame, an electric heating element consisting of a wire 23 of nichrome or other suitable material, said wire being wound in helical form about the exterior of said tubes. The terminals of the wire 23 are connected to a pair of binding posts 24 and 25, respectively, said posts passing vertically down through the lower frame member 15, 75 said terminals being held upon washers 26 by means of nuts 27 threaded on the inside portions of said posts.

70 In order to supply electric current to the heating element just described, a pair of conductors 28 and 29 are provided, said conductors being connected to a suitable source of current, such as a storage battery, magneto, etc., and also being connected to the binding posts 24 and 25. The terminals of the wires 28 and 29 are adapted to be seated upon washers 30 and 31, and are clamped tightly against said washers by knurled binding nuts 32 and 33 respectively.

75 The porcelain tubes 19, 20, 21, and 22 are held in position by a series of U-shaped clips 34 having their side arms seated in recesses in the inner legs of the wooden frame members 12, 13, 14, and 15, described above. The porcelain tubes are held in spaced relation from said frame members by four asbestos strips 36, upon which said tubes are seated. The direct heat rays from the heating wire wound on said porcelain tubes, are shielded from the glass panes 10 and 11 by side strips 37 and 38 of asbestos, whereby the danger of cracking the glass by overheating will be entirely prevented.

80 In order to provide ventilation for the interior of the double-walled compartment, a pair of ventilation holes 39 and 40 respectively are provided in the top and bottom frame members 12 and 15. By means of this construction air will continuously be drawn in through the hole 40, and will pass 110 upwardly through the heated compartment and out through the hole 39, thereby pre-

venting the air in said compartment from overheating the glass panes. If desired, a thermostat may be employed to automatically shut off the current in case the temperature becomes too high.

It may be desirable in some cases to assist the action of the heated glass panes by mechanically operated means. For this purpose, the device illustrated in Figs. 1 and 2 may be employed and comprises a vertical metallic scraper 41 having a sharpened edge 42 adapted to lie in contact with the front surface of the pane 10 of the windshield. The scraper 41 is provided at its end with an enlarged tapped collar 43, threaded upon a horizontal screw 44 extending the full length of the windshield, and journaled in the brackets 45 and 46 located at the opposite ends thereof.

The scraper 41 is adapted to be held in firm contact with the surface of the glass pane 10 by means of a resilient leaf spring 47 attached to the top of the collar 43 by means of screws 48. The horizontal screw 44 has one end extending beyond the bracket 46 and provided with a bevel gear 49, meshing with a gear 50 on the upper end of a vertical shaft 51 mounted to rotate in bearing brackets 52, said vertical shaft 51 being driven intermittently in opposite directions by any suitable mechanism not shown.

In operation when the current is turned on by a switch, not shown, the wire 23, coiled upon the shielded porcelain tubes, will become heated causing the air within the double-walled windshield to warm up and heat the glass panes 10 and 11. The size of the ventilation holes 39 and 40, and the amount of current sent through the wire 23 are made such as to maintain the glass

panes 10 and 11 at the most efficient temperature without overheating.

Under ordinary conditions, the scraper 41 will not be necessary, but when it is needed, as to remove excessive accumulations of ice, in a storm, the intermittent rotation of the shaft 51 will cause the screw 44 to move the scraper 41 back and forth along the front of the windshield—this operation being entirely automatic.

While there have been disclosed in this specification two forms in which the invention may be embodied, it is to be understood that these forms are shown for the purpose of illustration only, and that the invention is not to be limited to the specific disclosures but may be modified and embodied in various other forms without departing from its spirit. In short, the invention includes all the modifications and embodiments coming within the scope of the following claim.

Having thus fully described the invention, what is claimed as new, and for which it is desired to secure Letters Patent, is:

In a heated windshield, a compartment having front and rear panes of transparent material, a frame for holding said panes, a plurality of porcelain tubes disposed between said panes adjacent the edges thereof and within the frame opening, an electric heating wire coiled about said tubes, means for supplying current to said wire, and a shield of channel form in which said tubes are disposed with the web of the channel between said frame and tubes.

In testimony whereof, I have affixed my signature to this specification.

FLORA A. HEALY.
